RAZOR STROP

Filed Feb. 15, 1930

INVENTOR
WILLIAM G. WALLENBECK.

BY Albert C. Bell
ATTORNEY

UNITED STATES PATENT OFFICE

WILLIAM G. WALLENBECK, OF CHICAGO, ILLINOIS

RAZOR STROP

Application filed February 15, 1930. Serial No. 428,550.

My invention relates to an improved construction of razor strop consisting of a strop of flexible material for example leather, canvas or the like, by which an enclosing member 5 is made a part of the structure, so that the strop may be given small compass when desired, and surrounded by said member, which preferably is in the form of a strip of flexible material of sufficient length to encircle the 10 strop in its compact condition, and of sufficient width to protect the surface of the strop. My invention further consists in providing the enclosing member with fastening devices which may readily be used to hold the protective covering around the strop in its compact condition, which fastening devices preferably are of a kind to hold the protective covering in compact form when the strop is in use, so that both sides of the strop are 15 available quite as effectively as though the protective covering were not a part of the strop construction.

My improved strop construction is particularly of advantage where it is desired to carry 20 the strop in a traveling bag, since under such conditions it is desirable to have the strop in compact form and at the same time to hold it securely in compact form to prevent it opening and becoming mixed up with the other 25 contents of the bag. Furthermore, under such conditions, it is desirable to protect the surface of the strop to keep it clean and smooth and this is insured by the use of the protective covering referred to. In addition 30 to the advantages to the user of the strop, my improved construction affords an additional advantage to the manufacture of and dealer in these devices, by providing on the enclosing member, a substantial space available for 35 printed and advertising matter, which cannot be imprinted on the strop itself on account of the need of maintaining the surfaces of the strop smooth and clean for stropping 40 purposes.

45 While I am aware that it has been pro-

posed heretofore to provide enclosures of one kind or another for flexible razor strops in rolled or compact form, my improved construction has the advantage of the enclosing member being attached to the strop itself, so 50 that it is immediately available for use and cannot be lost.

My invention will best be understood by reference to the accompanying drawing showing a preferred embodiment thereof in which 55

Fig. 1 illustrates my complete strop construction in front elevation,

Fig. 2 is a sectional view of the protective member shown in Fig. 1 taken along the 60 line 2—2,

Fig. 3 shows a portion of my strop in rear perspective view with the protective member held by its fastening devices in a position permitting the ready use of both sides 65 of the strop,

Fig. 4 shows in a view similar to Fig. 1, the strop in partly rolled condition, and

Fig. 5 shows in perspective view, the strop in completely rolled condition and surrounded by the protective member in condition for 70 storing or traveling as desired.

Similar numerals refer to similar parts throughout the several views.

As shown in Fig. 1, my strop construction consists of a strop 10, formed of a strip of 75 flexible material adapted to stropping purposes, for example, leather, canvas or the like, having an eyelet 11 extending through one of its ends, which eyelet also extends through the corresponding end of a protective member 12, to hold said member securely to the strop at all times. The member 12 is preferably a strip of any suitable covering material, for example leather, leatheroid or fabric, which is of a length sufficient to encircle the 80 strop 10 in its rolled or folded condition, and of a sufficient width to completely protect the strop in that condition. While it is desirable that the width of the protective member shall be no less than the width of the strip 85 90

of material forming the strop 10, I do not limit myself to that width, as I may employ any other width in making the protective member, that will secure the desired protection for the strop in its folded or rolled condition.

To conveniently support the strop construction from a hook or otherwise while it is being used, I provide a string loop 13 extending through the eyelet 11 which has the effect due to the flexibility of the string, of a swivel construction, the ends of the string being held in place preferably by a metal sleeve 14 tightly clamped against them. To protect the string swivel construction against wear on the eyelet 11, I preferably extend a double portion of the string through the eyelet, since this is the point where the greatest wear comes on the swivel, on account of turning the strop over repeatedly while using it.

As more clearly shown in Fig. 2, I preferably secure to the member 12 adjacent its ends, fastening devices 15 and 16, adapted to interengage each other to hold the ends of the member 12 together. These devices may be the parts of a snap fastener, or any devices which may readily be engaged or disengaged from each other. Where, as in the case of snap fasteners, the fastener consists of male and female members, it will be understood that either member of the fastening device may be used at either end of the protective member 12.

The fastening devices connected with the member 12 are preferably of such a nature that when the strop is in use, the lower end of the flexible member may be rolled upwardly and the parts of the fastening devices may be secured together, as illustrated in Fig. 3, thus making available not only the front surface of the strop shown in Fig. 1, but also its rear surface shown in Fig. 3, which is desirable on account of the two sides of a strop frequently being intended for different purposes in sharpening razors or other keen edged tools.

It will be understood that in placing the strop 10 in condition to be surrounded by the member 12, the strop may be folded or rolled in any manner most convenient to the user, the principal consideration being that the strop shall be in sufficiently compact form so that the member 12 may surround the strop in its compact condition, so that its fastening devices may be brought into engagement with each other to hold the strop in its compact condition and protect it as described by the enclosing protective member. In view of this, I employ the term "compact condition" in the claim to signify any manner of rolling or folding that may give the strop a small bulk, permitting its being surrounded and held in that condition by the protective

member. I find it convenient to secure the compact condition of the strop referred to, by rolling it as indicated in Figs. 4 and 5, the strop being in partially rolled condition in Fig. 4 and in completely rolled condition in Fig. 5.

The rolling indicated in Fig. 4 is continued until the string swivel 13 is also included in the roll, and then the free end of the protective member 12 is wrapped around the roll so that the parts of its fastening devices 15 and 16 may be brought into engagement with each other as indicated in Fig. 5, to hold the protective member securely in place around the strop in its compact condition. In this form, the strop occupies a minimum of space, it may readily be stored or carried in a traveling bag and is protected from injury and kept clean. At the same time, the rolling of the strop does not in any way injure it, and when the parts 15 and 16 of the fastening devices are separated from each other, the strop readily opens into its proper position for use.

Besides having the advantages referred to, the material of the protective member 12 may be selected if desired, with a view to readily receiving the imprint of advertising matter on one or both of its surfaces. If desired such matter may be arranged on the outer surface of the protective member so that it is displayed when the strop is in its condition illustrated in Fig. 5. Again, if preferred, stropping directions may be imprinted either on the outer surface of the protective member or on the inner surface, which is outermost for the relation of the parts shown in Fig. 3. Since the purpose of the protective member 12 is to enclose and protect the strop in its compact condition, the material of said member may be selected solely from the standpoint of artistic appearance, or if printed matter is desired on said member, from the standpoint of the facility with which the surfaces of the protective member will receive the imprint of the printed matter, in addition to having the desired characteristics protecting the structure as a whole from wear and injury.

It will also appear that my improved strop construction, in addition to having the advantages set forth, is economical to manufacture and does not necessarily increase the bulk of the strop in its compact condition to an appreciable extent.

While I have shown my invention in the particular embodiment above described, it will be understood that I do not limit myself to this exact construction as I may employ equivalents known to the art at the time of the filing of this application without departing from the scope of the appended claim.

What I claim is:

In a strop construction, the combination of a strop comprising a first strip of flexible

material for stropping purposes, a protective member comprising a second strip of flexible material to surround said first strip in rolled condition, means securing said strips together, and separable fastening devices carried by said second strip for holding it around said first strip in rolled condition, said second strip being shorter than said first strip and of a length permitting it to surround said first strip in rolled condition.

5 10 In witness whereof, I hereunto subscribe my name this 3rd day of February, A. D. 1929.

15 WILLIAM G. WALLENBECK.
